United States Patent Office

Des. 215,996

Patented Nov. 11, 1969

215,996

KNIFE

Marion Weeber, New York, N.Y., assignor to American Home Products Corporation, New York, N.Y., a corporation of Delaware

Filed Nov. 12, 1968, Ser. No. 14,392

Term of patent 14 years

Int. Cl. D7—03

U.S. Cl. D95—3

FIG. 1 is a side elevational view of a knife showing my new design.

FIG. 2 is a top plan view thereof.

FIG. 3 is a bottom plan view thereof.

FIG. 4 is a transverse section taken on line 4—4 of FIG. 1.

FIG. 5 is a transverse section taken on line 5—5 of FIG. 1.

FIG. 6 is a transverse section taken on line 6—6 of FIG. 1.

I claim:

The ornamental design for a knife, as shown.
